UNITED STATES PATENT OFFICE.

ARTHUR FORNEY, OF BALTIMORE, MARYLAND.

CHECK-CONTROLLED VENDING MACHINE.

Application filed May 26, 1927. Serial No. 194,325.

This invention relates to check controlled vending machines and has for an object to provide a machine of unusual elasticity as to the coins employed and the merchandise delivered.

A further object of the invention is to provide a coin controlled vending machine which may be adjusted to vend packages of various sizes and with improved means for controlling the delivery of the package.

A further object of the invention is to provide a coin controlled vending machine which may be adjusted from time to time to operate with a different number of coins as the price of the commodity vended may fluctuate.

A further object of the invention is to provide a vending machine actuated by the introduction of a plurality of coins with improved means for employing the coins in the actuation of the mechanism.

With these and other objects in view, the invention comprises certain novel parts, elements, units, combinations, constructions, interactions, mechanical movements and functions as disclosed in the drawings together with mechanical and functional equivalents thereof, as will be hereinafter more fully described and claimed.

In the drawings:

Figure 1 is a view partly in side elevation but largely in vertical section of the improved coin controlling mechanism.

Figure 2 is a view of the device in side elevation.

Figure 3 is a view of the device in edge elevation as indicated by arrow 3 at Figure 2.

Figure 4 is a top plan view of the device.

Figure 5 is a sectional view taken on line 5-5 of Figure 1.

Figure 6 is a perspective view of the commodity detaining and separating instrumentality.

Figure 7 is a perspective view of the coin detaining and releasing mechanism.

Like characters of reference indicate corresponding parts throughout the several views.

The improved coin controlled vending machine which forms the subject matter of this application is intended to be employed in conjunction with any form of commodity retaining stack, shelving or the like, indicated conventionally at 10, it being understood that the proportions and relations to the ma-

chine will vary according to the commodity and other conditions.

To the side of this stack 10 a framework 11 is secured, which carries the coin receiving and actuating structure.

This coin receiving and actuating structure comprises a slide 12 having a handle or other means for manipulating, indicated at 13, and movable from the normal or inoperative position shown at Figure 2 to the 65 fully inserted or operative position shown at Figure 1.

This slide 12 is provided with a coin slot 14 into which the coins are inserted. This coin slot 14 in normal inoperative position 70 registers with the coin magazine 15 so that coins introduced into the coin slot 14 drop by gravity directly through into the magazine 15.

The frame 11 is provided with a plurality 75 of grooves 16 which are spaced properly in accordance with the diameter of the coin to be employed in the particular organization, such coins being indicated at 17 in Figures 1 and 2.

The slide 12 has a right angular offset detent 19 fitting into any one of the several grooves 16 as the bar 18 may be adjusted by means of the slot 20 and screw 21. The grooves 16 intersect the coin magazine 15 so that the detent 19 sliding in any one of the grooves 16, when in normal position, is so placed as to detain the coins which are dropped through the coin slot 14 into the magazine 15 and the number of coins which 90 may be dropped into the magazine 15 will be determined by the position of the detent 19 in some one of the grooves 16.

As shown at Figures 1 and 2, the device is adjusted so that the magazine 15 will contain two inoperative coins 17 while the third coin 22 will originally occupy the position shown at 22' in Figure 1 and in such position as to be engaged by the shoulder 23 forming one of the sides of the coin chute 100 14. When, therefore, the slide 12 moves in the direction of the arrow, the shoulder 23 will push the coin 22 from off the top of the idle coins on to the ledge 24 in which position it will be projected into the outer 105 edge of the slot 25 in the sliding block 26. The shoulder 27 of this sliding block 26 will tend to resist the further movement of the coin 22 but, by reason of the sliding block 26 being held to position only by the spring 110

28, the block will yield and move to the position shown at Figure 1 until the coin 22 is in position to enter the slot 29 in the frame 11, whereupon the coin will be forced 5 through the slot 29 and will release the sliding block 26 which will be returned by its spring to normal position.

As a simultaneous action, the movement of the slide 12 carrying with it the bar 18 10 will remove the detent 19 from detaining position under the idle coins 17 which will all drop through the coin magazine into a receptacle 30 together with the coin 22 which has likewise been discharged into the same receptacle. 15

As will be noted especially from Figures 5 and 4, the sliding block 26 is provided with a beveled or inclined cam side 31 and a pin 32 is mounted to slide in the frame 11 to project into and out of the commodity stack 10 with a spring 33 tending to hold the pin with its head 34 slidably in engagement with the cam 31. In its normal position, the pin 32 is held by the sliding block 26 with its end 25 projected into the commodity stack as indicated in dotted lines at Figures 3 and 4. When, however, the sliding block is moved back by the actuation of the device with a coin in proper position so that the sliding 30 block is in the position shown at Figures 1 and 5, the head 34 of the pin 32 slides down the incline 31 of the sliding block and is withdrawn from the commodity stack, as shown at Figure 5, so that a package of commodity within the stack, indicated at 35, would drop downwardly into the accessible opening 36.

To prevent other commodity packages from also being discharged and delivered at the same time, the next commodity package above indicated as 35' is detained temporarily by means of a plate 36 which is secured to the slide 12 by means of an offset 45 37, slotted as at 38 to make it adjustable upon the slide 12 for packages of different sizes. As the slide 12 is moved in, therefore, to withdraw the pin 32 from its supporting position, the plate 36 is inserted between the lowermost and its next above package so that 50 the lowermost package may freely drop while the package above is retained against such dropping. Immediately upon the discharge of the coin 27, the sliding block 26 will snap back into position, thus permitting the pin 32 to again assume its detaining position, so that, when the slide 12 is drawn outwardly and the plate 36 withdrawn from supporting position under the package 35', the pin 32 is in position to restrain the stack 55 of commodity packages from dropping except for the distance necessary for the delivery of the next item.

In operation, the device will be attached to any convenient form of commodity stack 60 which will be determined wholly by the size,

shape and contour of the packages. The device will be so attached that the pin 32 will be in proper position for maintaining the commodity stack and the plate 36 will be adjusted up or down as may be made necessary by the size and shape of the package so as to properly insinuate itself between the lowermost and superposed package when operated. 70

It being determined also how many of a particular denomination of coin will be required to purchase one package of the commodity, the bar 18 will be adjusted so that the detent 19 will occupy the proper slot to support the required number of coins, and it is to be understood that the showing of two coins in the drawings is merely indicative and that the number may be more or less according to the setting and adjusting of the bar 18 providing for the detent 19 to be in 80 position to support the coins of the magazine at any given position. 85

It is intended that this device shall be employed for the vending of commodities, the price of which may vary from day to day, while the packages themselves remain substantially constant in size, so that once adjusted as to the size of the package, a periodical adjustment of the bar 18 to provide for the actuation of the device by a greater or lesser number of coins may be accomplished as occasion may make necessary. 90 95

What I claim to be new is:

1. A coin controlled vending machine comprising a frame having a coin magazine intersected by a plurality of slots perpendicular to the magazine chamber, a manually movable part having a coin slot registering at times with the coin magazine, and a detent adjustable to move in an elected slot 100 and to support a predetermined elected number of coins in the magazine, means including said movable part to employ the uppermost coin for actuating the delivery mechanism and to move the detent from coin supporting position, and means to discharge the employed coin together with the other coins in the magazine. 105

2. A coin controlled vending machine comprising a frame having a coin magazine 110 therein, a manually movable part, means carried by the movable part adjustable to support a predetermined elected number of coins in the magazine, a block slidably mounted, means to employ one of the coins 115 to connect the movable part with the sliding block, and means actuated by the movement of the sliding block for delivering commodities. 120

3. A coin controlled vending machine 125 comprising a frame having a coin magazine intersected by a plurality of grooves perpendicular to the chamber of the magazine, a movable part having a coin slot registering at times with the coin magazine, a member 130

carried by the movable part having a detent adjustable to move in an elected slot, a sliding block, means to employ the uppermost coin in the magazine as a connector between the movable part and the sliding block, means controlled by the movement of the sliding block to release a commodity package, and means carried by the movable part for supporting the commodity next above that discharged.

4. The combination with a commodity stack of a coin controlled delivery mechanism associated with said stack, said delivery mechanism comprising a frame, a coin

magazine contained in said frame, a movable part, a sliding block, means to employ a coin in the magazine as a connector between the movable part and the sliding block, a pin inserted into the commodity stack and movable longitudinally by the movable block, and a separating and supporting plate carried by the movable part inserted into the commodity stack, properly spaced from the pin to deliver a predetermined quantity of commodity.

25
In testimony whereof I affix my signature.

ARTHUR FORNEY.
